[57] ABSTRACT

A support system is described which is capable of maintaining a platform such as a workpiece holding table, in a fixed plane while it moves along a path in that plane. The platform is supported with respect to a base by means of interconnecting mechanisms made up of panels hingedly connected to each other and to control braces which vary the articulation of the panels. The panels are thicker at the center than at the edges and in assembly they cooperate to produce an exceptionally rigid structure.

PLATFORM SUPPORT SYSTEM

This invention relates to support structures and more particularly it concerns a platform supporting system capable of maintaining a platform rigidly fixed from all movement except translation in a given plane.

The invention is useful in industries where articles must be transferred with a high degree of precision from one location to another along a straight path of movement. Thus for example, the invention may be used in the supporting of an assembly to be welded at several displaced points therealong. In such case, the assembly may be mounted on a platform supported according to the present invention; and the platform, with the assembly thereon, can be moved along under a fixed welding head.

Other uses of platforms supported according to the present invention may include the mounting tool heads on articles to be processed by tools so that successive tool operations may be carried out at different locations along a fixed plane. The invention is also suited to conveyor type applications where articles must be transferred from one location to another, such as in the loading and unloading of trucks, furnaces, and ovens, for example.

One feature of the present invention is that it permits a platform to be moved easily along a given path in a fixed plane while at the same time being highly resistant to forces outside the given path. Thus a platform supported according to the present invention resists lateral forces, rotational forces and twisting and bending forces. In addition, the platform movement according to the present invention is obtained exclusively by means of hinge or pivot type interconnections, so that all sliding and rolling motion, which is susceptible to dirt and other foreign material, is avoided.

In the past, platforms had been supported for movement in a fixed plane by means of slideways. Any rigidity which this arrangement provided was achieved only at the expense of high frictional resistance to movement along the desired path. Roller and ball bearings have been proposed as a means of overcoming this frictional resistance. However, this results in a greater susceptibility to wear and ultimate loss of rigidity since it permits dirt and other foreign materials to contact the sliding or rolling surfaces.

Pivotal or swinging type supporting arrangements for moving platforms have also been proposed. These arrangements, for the most part, however, do not maintain the platform in a fixed plane. Moreover, these arrangements lack sufficient rigidity for precision operation.

Various suspension systems have been proposed using pivotally connected links to obtain straight line motion. One such system shown in U.S. Pat. No. 2,683,481 to A. Lorenz, is used for mounting a glider type swing or chair. The Lorenz system employs four linkage mechanisms known as "Peaucellier link mechanisms," at the four corners of a seating platform. These Peaucellier link mechanisms each comprise four equal length links pinned together to form a rhombus, a pair of equal length outer links pinned together at one end and pinned at their other end to diagonally opposite corners of the rhombus, and a center link connected between another corner of the rhombus and a fixed link. When either the remaining corner of the rhombus, or the corner formed by the pinned together ends of the

outer links, is maintained at a proper location with respect to the fixed pivot, the other will be confined to movement in a straight line. Although a Peaucellier link mechanism does provide for straight line motion using only pivoted elements, its incorporation of multiple links and pivots, which are not fixed, leaves it susceptible to forces outside the normal path of link movement. The mechanism is inherently non-rigid. Even the use of four such mechanisms at the corners of a member such as a chair seat in the above mentioned Lorenz patent does not overcome the problem of lack of rigidity. The supported member remains vulnerable to lateral and turning forces.

The present invention is directed to overcoming these problems of the prior art in that it provides a support mechanism for mounting platforms in an inherently rigid manner so that they are resistant to forces in all directions except that along a given path of movement. The platform mounting arrangement of the present invention, moreover, requires no sliding or rolling movement to maintain the platform in a fixed plane.

According to the present invention, there is provided an elongated base member, an elongated platform member and interconnecting mechanisms between the two members which confine their relative movement to a given path in a fixed plane. At least one of the interconnecting mechanisms includes first and second support panels each extending between parallel hinge lines displaced at a first distance from each other. These panels are also hingedly connected to one of the members and to each other along one of the hinge lines, which extends across the width of the member. The interconnecting mechanism further includes third and fourth support panels each also extending between parallel hinge lines displaced a second distance from each other. The third and fourth panels are hingedly connected to the other of the members and to each other along one of their hinge lines, which also extends across the width of the other member. The first and third panels and the second and fourth panels, respectively, are hingedly connected to each other along their remaining hinge lines. A pair of control braces are provided. These control braces are of the same length as the first distance, i.e., the width of the first and second panels; and they are pivotally connected to one end, respectively, to the referred to remaining hinge lines of the panels. The other ends of the control braces are pivotally connected to each other and to one end of a control link. The other end of the control link is connected to a pivot fixed to the other member along a line extending out from the plane of the member and at a distance from the member equal to the length of the control link.

The first, second, third and fourth support panels are of a construction such that they are each of greatest thickness in the center and least thickness along the edges and such that they are all resistant to compressive forces acting between their hinge lines; and they are also resistant to tension, torsion and bending forces. As illustratively embodied, these panels may be of open framework construction comprising bars and struts arranged in the form of octahedrons or pairs of superimposed tetrahedrons. The panels may also be made of sheet material shaped to the same overall configuration. The control braces and connecting link need be resistant only to compression and tension. The third and fourth panels are provided with openings which

permit them to swing through the fixed pivot thereby allowing for a maximum platform travel distance. These openings are located at the center of the mutually hinged together edges of the third and fourth panels and therefore they have minimal effect upon the rigidity of these panels.

In the above described panel arrangement no single element connection exists between the base and the platform being supported. That is, any connection between the base and the platform requires the presence of at least two panels, hingedly connected to each other and to the base and platform respectively. Since each connection must include two panels and three hinges, a problem of stability would be expected, as in the prior art. However, with the present invention an inherent rigidity is achieved because the four panels cooperate to form a box-like construction which itself is inherently rigid.

According to a further feature of the present invention, only a single interconnecting mechanism as above described need be provided; and one or more other interconnecting mechanisms may be formed of a pair of further panels having edge to edge distances the same as the first and third panels respectively. These further panels are hinged together and to the base and platform members in the same manner as the first and third panels; and a connecting bar is pivotally connected at one end of the junction between the further panels and the corresponding junction between the first and third panels.

There has thus been outlined rather broadly the more important features of the invention in order that the detailed description thereof that follows may be better understood, and in order that the present contribution to the art may be better appreciated. There are, of course, additional features of the invention that will be described hereinafter which will form the subject of various ones of the claims appended hereto. Those skilled in the art will appreciate the conception upon which this disclosure is based may readily be utilized as a basis for the designing of other structures for carrying out the several purposes of the invention. It is important, therefore, that the claims be regarded as including such equivalent construction as do not depart from the spirit in scope of the invention.

A number of embodiments of the invention have been chosen for purposes of illustration and description and are shown in the accompanying drawing forming a part of the specification wherein:

FIG. 1 is a side elevational view illustrating a platform support system in which the present invention is embodied;

FIGS. 2A, 2B and 2C are fragmentary views of one interconnecting mechanism, utilized in the embodiment of FIG. 1, at different stages of platform movement;

FIG. 3 is a fragmentary perspective view illustrating the construction of one of the interconnecting mechanisms used in the embodiment of FIG. 1;

FIG. 4 is a fragmentary exploded perspective view showing the construction and interconnections of a panel forming a portion of an interconnecting mechanism in the embodiment of FIG. 1;

FIG. 5 is an enlarged fragmentary view taken along line 5-5 of FIG. 3;

FIG. 6 is an enlarged fragmentary view taken along line 6-6 of FIG. 3;

FIG. 7 is an enlarged fragmentary view taken along line 7-7 of FIG. 1;

FIG. 8 is a side elevational view of FIG. 7;

FIG. 9 is a side elevational view illustrating a second embodiment of a platform support system according to the present invention;

FIG. 10 is a view taken along line 10-10 of FIG. 9;

FIG. 11 is a fragmentary perspective view taken along line 11-11 of FIG. 10;

FIG. 12 is a view taken along line 12-12 of FIG. 9;

FIG. 13 is a view taken along line 13-13 of FIG. 9;

FIG. 14 is a view taken along line 14-14 of FIG. 9;

FIG. 15 is a perspective view of a strap type hinge which may be used to connect various panels together in the illustrated embodiments; and

FIG. 16 is a section view taken along line 16-16 of FIG. 15.

The platform support system of FIG. 1 comprises a horizontal platform 20 mounted above a base 22 to move back and forth in the direction of an arrow A in a plane parallel to that of the base. The platform 20 is supported above the base 22 by means of a pair of interconnecting mechanisms 24.

Each interconnecting mechanism 24 comprises first and second outer support panels 26 and 28 hingedly connected to each other and to the platform 20 along a platform hinge line 30. Third and fourth outer support panels 32 and 34 are hingedly connected to each other and to the base 22 along a base hinge line 36. The third and fourth panels, which are longer, in the plane of FIG. 1 than the first and second panels, are hingedly connected, respectively, to the third and fourth panels along the panel hinge line 38 and 40. A pair of interconnecting braces 42 and 44, are connected to the support panels 26, 28, 32 and 34 at the hinge lines 38 and 40. These interconnecting braces, which are equal in length (in the plane of FIG. 1) to that of the first and second support panels 26 and 28, are pivotally connected to each other and to a control link 46 at a pivot joint 48. The control link 46 in turn is pivotally connected at a pivot point 50 to a fixed brace 52 mounted firmly on the base 22. The brace 52 is located such that the pivot point 50 lies along a line extending perpendicular from the base hinge line 36; and the pivot point 50 is equidistant from the hinge line 36 and the pivot point 48. The brace 52 may be supported by means of a diagonal strut 54 extending from the base.

With the arrangement described above, the platform 20 is free to move back and forth along a fixed plane, in the direction of the arrow A while always remaining parallel to and at a fixed distance from the base 22.

The action of the above described interconnecting mechanism 24 during platform movement is illustrated in FIGS. 2A, 2B and 2C. As can be seen from these FIGS., the first and second support panels 26 and 28 and the interconnecting braces 42 and 44 are of the same length (in the plane of FIG. 2); and they combine to form a rhombus. The pivot point 50 corresponds to a fifth hinge line. During movement of the platform 20 the third and fourth support panels 32 and 34 pivot above the base hinge line 36 and tend to swing the rhombus around with them. However, during this

movement, the control link 46, whose fixed pivot point 50 is removed from the base hinge line 36, operates in conjunction with the third and fourth support panels 32 and 34 to change the diagonal relationships of the rhombus. That is, when the interconnecting mechanism extends upright as shown in FIG. 2B, i.e., when the platform hinge line 30 is directly above the base hinge line 36, the rhombus is horizontally extended, with the hinge lines 38 and 40 being farthest apart from each other. As the platform 20 moves either to the left or to the right as shown in FIGS. 2A and 2C, the third and fourth support panels 32 and 34 swing in the same direction; and the control link 46 serves to bring the hinge lines 38 and 40 closer together thus extending the rhombus in a generally vertical direction as shown. It will be seen that during these movements of the interconnecting mechanism 24, the platform hinge line 30 is confined to movement along a horizontal line as viewed in FIG. 2. This will occur so long as the panels 26 and 28 and the control braces 42 and 44 have the same length, in the place of FIG. 2; and the panels 32 and 34 are equal in length to each other and the distance from the pivot joint 48 to the pivot joint 50 is the same as the distance from the pivot point 50 to the base hinge line 36.

It should be understood that either or both of the interconnecting mechanisms may be inverted and the same platform movement as described above will result. Also if only one interconnecting mechanism is inverted a certain self balancing characteristic will be achieved.

The platform movement may be produced by any automatic or manual means (not shown) which will exert a force on the platform in the desired direction. Since no sliding or rolling action takes place during the movement and since all relative movement between elements is pivotal, the forces required to effect platform movement are minimal.

Turning now to FIG. 3, it will be seen that the four panels 26, 28, 32 and 34 extend across the width of the platform 20 and the base 22. Also, the first and second panels 26 and 28 are provided with fittings 55 and 56, respectively, which are pinned to each other by means of a pin 51 extending along the platform hinge line 30. The pin 51 passes through the fittings 55 and 56 and into a support bar 57 which is connected to the platform 20 by means of a pair of collars 58. The assembly of these elements is best seen in FIG. 6.

It will be seen in FIG. 3 that the various support panels 26, 28, 32 and 34 of the interconnecting mechanism 24 are of frame-like construction. More particularly, they are constructed such that they have maximum thickness in the center and are thinner nearer the various hinge lines 30, 36, 38 and 40.

In the present embodiment, each of the panels is made up of an assembly of tubular elements arranged as an octahedron, or four superimposed tetrahedrons.

The construction of an individual support panel is best seen in the exploded perspective view of FIG. 4. As there shown, a typical panel, e.g., the third panel 32, comprises a pair of heavy tubular side members 59 and 60 which extend parallel to each other between the hinge lines 36 and 38. The ends of each of the side members 59 and 60 are provided with lower and upper male and female fittings 61 and 62 for hinge type interconnection with adjacent panels, control braces, plat-

form or base members. Two diagonal struts 64 are welded at one end to the base of each of the fittings 61 and 62; and these struts extend to the upper and lower ends of a spreader bar 66 which is located centrally of the panel and extends perpendicular to the plane of the panel.

As can be seen in FIG. 4, the lower end of the first panel 26 is of similar construction to that of the third panel 32; and is provided with a pair of male fittings 68 which form a hinge type interconnection with the upper female fittings 62 of the third panel 32. Upper hinge pins 70 extend through these fittings and into upper collars 72 mounted on the ends of an upper spacer bar 74 which extends between the fittings. As shown, two branches 42a and 42b of the interconnecting brace 42 are welded to the collars 72. The interconnection between the fittings 62 and 68, the collar 72 and the pin 70 is shown in assembly in FIG. 5. A similar interconnection between fittings 55 and 56 at the upper ends of the first and second panels 26 and 28 (FIG. 6).

The lower male fittings 61 of the third panel 32 are hingedly connected to corresponding fittings (not shown) of the fourth panel 34 in a manner similar to that described above. Lower hinge pins 76 extend through the fittings and into collars 78. These collars are mounted on the ends of a lower spacer bar 80 which is secured to the base 22.

It will be appreciated that the tubular side members 59 and 60, the upper and lower spacer bars 74 and 80, the struts 64 and the spreader bar 66 cooperate to form a space frame which may be defined as an octahedron or four interconnected tetrahedrons. This frame, which is thicker in the center than at the edges, is inherently rigid and is resistant to compressive forces between their adjacent hinge lines, tensile forces and bending and twisting forces. Each of the four support panels 26, 28, 32 and 34 is of similar construction. Moreover, since these panels are connected along parallel hinge lines, they cooperate to form a box-like structure which maintains an overall rigidity against all forces except those in the direction of pivotal movement about the hinge line.

The construction and interconnection of the interconnecting braces 42 and 44 and the control link 46 will now be described with reference to FIGS. 7 and 8. As can be seen in FIG. 7 the interconnecting braces 42 and 44 are formed tubular steel and each comprises a pair of branches 42a and 42b and 44a and 44b. The two branches of each brace are connected together at a yoke 82. The yokes 82 are bolted to male and female pivot fittings 84 and 86; and these in turn are pinned together along with an outer fitting 88. As shown in FIG. 8, the outer fitting 88 is secured to the upper end of the control link 46.

Reverting now to FIG. 3 it will be seen that the fixed brace 52 to which the lower end of the control link 46 is pivoted, is made up of a pair of diagonally extending branches 52a and 52b which come together at the pivot 50. These branches 52a and 52b are also welded to the diagonal strut 54.

It will be appreciated that while the outer support panels 26, 28, 32 and 34 are all of special construction; i.e., with a thicker center, so as to enable them to resist tension, compression, bending and twisting, the interconnecting braces 42 and 44 and the control link 46 may be of more nearly planar construction and resis-

tant only to tensile and compressive forces. Thus, the interconnecting braces 42 and 44 may come together and act incorporation with the control link 46 and the fixed brace 52 at a central location so that minimum interference will be encountered between them and the outer support panels. As can be seen in FIG. 2, the third and fourth outer support panels 32 and 34 are open near the bottom center thereof thereby permitting them to pass over the fixed brace 52 without interference.

While the various outer support panels 26, 28, 32 and 34 of the embodiment described above are of open framework construction, it is to be understood that the principles of the present invention may be realized with other forms of inherently rigid panel-like support members which are inherently rigid and resistant to compressive, tensile, bending and torsional forces.

A base and panel interconnecting mechanism utilizing an alternate form of panel construction is illustrated in FIGS. 9-14.

As can be seen in FIG. 9 a platform member 90 is maintained at a fixed distance above a base member 92 by means of an interconnecting mechanism 94 which is hingedly connected to the platform member 90 along an upper hinge line 96, and to the base member 92 along a lower hinge line 98. The interconnecting mechanism 94 includes first and second outer support panels 100 and 102 hingedly connected to each other and to the platform member 90 along the upper hinge line 98, and third and fourth outer support panels 104 and 106 hingedly connected to each other and to the base member 92 along the lower hinge line 98. The first and third outer support panels 100 and 104 are hingedly connected to each other along a third hinge line 108 while the second and fourth outer support panels are hingedly connected to each other along the fourth hinge line 110.

First, second and third control panels 112, 114 and 116 are hingedly connected to each other along a control panel hinge line 118. The opposite ends of the first and second control panels 112 and 114 are hingedly connected to the outer support panel along the third and fourth hinge line 108 and 110 respectively. The remaining edge of the third control panel 116 is hingedly connected to a fixed abutment 120 along an abutment hinge line 122. The fixed abutment 120 is permanently secured to the base member 92 and the abutment hinge line 122 extends above the lower hinge line 98 by a distance equal to the distance between the control panel hinge line 118 and the abutment hinge line 122.

As in the previous embodiment, all of the hinge lines 96, 98, 108, 110, 118 and 122 are mutually parallel. Further, as in the preceding embodiment, the first and second outer support panels 100 and 102 and the first and second control panels 112 and 114 are all of the same length so that the distances between the various hinge lines 96, 108, 118 and 110 are all the same. The third and fourth outer support panels 104 and 106 are of the same length but are longer than the other panels.

It will readily be seen that the action of the panels to control the spacing between the platform member 90 and the base member 92 during lateral movement of the platform member is the same as that of the open framework embodiment of FIGS. 1-8.

The essential difference between the present embodiment and that of FIGS. 1-8 lies in the individual panel

construction used in the interconnecting mechanism. Whereas the various support and control panels of the preceding embodiment were constructed according to an open framework arrangement, their corresponding panels in the present embodiment are constructed of sheet material. In both cases, however the various panels are thickest in their center region and are thinnest along their edges. In addition, the various panels of the present embodiment follow the same general contours

10 as the open framework panels of the preceding embodiment. That is, the sheet material panels of the present embodiment have a configuration similar to that which would result if sheet material were stretched over the panel struts and bars and then stiffened. In 15 such case the struts and bars could be removed without substantial loss of strength.

FIG. 10 illustrates a plan view of the first outer support panel 100. As can be seen the panel 100 is of generally rectangular configuration and is formed on one 20 side by a composite of four triangular shaped sections 124 which slope in pyramid fashion from an apex 126 at the center of the panel down to the edges of the panel. This arrangement is repeated on the opposite side of the panel as can be seen in the sectional perspective view of FIG. 11. The material of the panels may be any stiff sheet material such as metal or plastic; and its thickness will be determined according to the strength required. It has been found however that relatively light gauge material can be fabricated into panels 25 of very high strength utilizing the construction illustrated.

Turning now to FIG. 12, the second control panel 114 is shown in plan view to be shaped as a trapezoid. Thus, the panel 114 extends from a wide edge 128, 30 which lies along the fourth hinge line 110, down to an opposite narrow edge 130, which lies along the control panel hinge line 118. The second control panel 114 is also formed of generally triangular sections 132 which extend from an apex 134, constituting the thickest portion of the panel, down to the panel edges. It will be seen from FIG. 9, however, that the first and second control panels 112 and 114 are flat along their lower surfaces. This provides clearance in the vicinity of an angle α so as to provide clearance with respect to the third and fourth outer support panels 104 and 106 and thereby afford maximum freedom of movement of the system.

The third control panel 116 is illustrated in plan view in FIG. 13. It will be seen that the overall configuration of this control panel is similar to that of the first and second control outer support panel 100 and 102 with the exception that the third control panel 116 is shorter and narrower than the other panels.

Turning now to FIG. 14, the fourth outer support panel 106 can be seen in plan view to be of substantially the same construction as the other panels described above. The fourth outer support panel 106, however, is provided with a triangular shaped cutout 136, which accommodates the fixed abutment 120, and the abutment hinge line 122 (not shown) during pivoting movement of the panel about the lower hinge line 98. This permits the same extensive movement which characterizes the embodiment of FIGS. 1-8.

The various panels described above may be hinged together in any suitable manner. FIGS. 15 and 16 illustrate a strap hinge 140, which may be utilized to provide this interconnection. The strap hinge 140 com-

prises an elongated central spine 142 and a plurality of flanges 144 extending radially out from the spine. The spine and flanges may be of integral construction so that the hinging action takes place by bending of the flanges in the vicinity of the spine. Various types of plastic are suitable for this type of hinging action. The hinge arrangement shown in FIGS. 15 and 16 is especially well suited for the present invention because most of the hinge lines require the relative interconnection of three separately pivoting elements. Also, the particular mechanism utilized herein does not require any of the relatively pivoted elements to reverse their relative positions. Accordingly special complex hinges whose various elements must pass by each other are not needed.

FIG. 9 illustrates a further aspect of the present invention. As shown in FIG. 9, there is provided a master-slave type interconnecting mechanism arrangement which substantially simplifies the construction of the platform support system while maintaining the same rigidity and precision of movement as in the preceding embodiment. In the master-slave interconnecting mechanism arrangement of FIG. 9, the interconnecting mechanism 94 serves as a master while a second interconnecting mechanism 160 serves as a slave. The slave mechanism 160 comprises upper and lower panels 162 and 164 of the same size, respectively as the second and third panels 102 and 106, respectively, of the first interconnecting mechanism. The upper and lower panels 162 and 164 are hingedly connected to each other and to the platform and base along hinge lines 166, 168 and 170 parallel to the hinge lines of the master mechanism 94. A connector bar 172 is hingedly connected between corresponding points on the master and slave interconnecting mechanism 94 and 160. This connector bar, as shown, is connected between the hinge lines 110 and 168 of the two interconnecting mechanisms, although it may be connected at any other corresponding points of the two mechanisms. Essentially, the connector bar maintains the corresponding panels of the two interconnecting mechanisms parallel to each other so that the slave interconnecting mechanism 160 serves to follow the master mechanism thereby to maintain the platform 90 parallel to and at a fixed distance from the base 92 during forward and backward movement the main interconnecting mechanism serves as a master. In this way a substantial savings in components is achieved.

It will be noted that the inherent rigidity afforded by the principles of the present invention permits of considerable flexibility of application. For example the platform support system of either FIG. 1 or FIG. 9 can be positioned with the base member in a vertical plane and with the various hinge lines extending vertically. In such case all gravity components which could affect the force necessary to operate the system are eliminated and yet the system remains free from binding or other effects of distortion.

Various embodiments of the invention have been chosen for purposes of illustration and description, and are shown in the accompanying drawings, forming a part of the specification, wherein:

I claim:

1. A platform support system for mounting a platform for movement along a given path in a fixed plane with respect to a base while maintaining same braced against other movement, said system comprising a pair

of interconnecting mechanisms each interconnecting said platform and base, at least one of said mechanisms comprising first and second outer support panels rigidly resistant to bending and twisting and hingedly connected at their edges to each other at displaced locations along a first hinge line, third and fourth outer support panels also rigidly resistant to bending and twisting and hingedly connected at their edges to each other at displaced locations along a second hinge line parallel to said first hinge line, said first and third panels being hingedly connected to each other at their remaining edges at displaced locations along a third hinge line and said second and fourth panels being hingedly connected to each other at their remaining edges at displaced locations along a fourth hinge line, said third and fourth hinge lines each being parallel to and located a first distance from said first hinge line, said third and fourth hinge lines each being located at a second distance from said second hinge line, a pair of control braces pivotally connected to each other along a fifth hinge line parallel to said first, second, third and fourth hinge lines, said control braces being pivotally connected to said outer support panels along said third and fourth hinge lines respectively, said fifth hinge line being displaced from said third and fourth hinge lines by said first fixed distances, a control link pivotally connected between said fifth hinge line and a pivot fixed with respect to said second hinge line, the distance from said fifth hinge line to said pivot being equal to the distance from said pivot to said second hinge line, means hingedly connecting said panels, at said first and second hinge lines, between said platform and base, the other interconnecting mechanism being articulated between said base and platform and means causing movements of said other mechanism to conform to movements of said one mechanism.

2. A platform support system according to claim 1 wherein said outer support panels are each of greater thickness at the center thereof than at their edges and are of a construction resistant to compression forces between the hinge lines, and resistant to tensile forces and bending and twisting forces.

3. A platform support system according to claim 1 wherein said outer support panels extend across the width of said platform.

4. A platform support system according to claim 3 wherein said control link and fixed pivot are positioned approximately midway across the width of the panels and wherein said third and fourth panels have openings extending from their base connected edges for allowing said panels to swing over said control link and fixed pivot.

5. A platform support system according to claim 4 wherein each of said control braces extend diagonally from said control link to out to the side edges of said panels at said third and fourth hinge lines.

6. A platform support system according to claim 2 wherein said outer support panels are of open framework construction comprising side elements and diagonal struts which cooperate to form octahedrons.

7. A platform support system according to claim 6 wherein each of said outer support panels is provided with fittings at the ends of said side elements, said fittings being pinned to corresponding fittings in an adjacent panel.

8. A platform support system according to claim 7 wherein said control braces each comprise a pair of

branches extending diagonally from said control link to collars adjacent the fittings on said outer support panels.

9. A platform support system according to claim 2 wherein said outer support panels are of flat sheet material segments arranged to form polyhedrons.

10. A platform support system according to claim 2 wherein said control braces are panels of sheet material segments arranged to form polyhedrons.

11. A platform support system according to claim 10 wherein said outer support panels and control braces are hinged together with strap type hinges.

12. A platform support system according to claim 1 wherein the other interconnecting mechanism comprises a pair of further panels hingedly connected to each other and to said platform and base respectively, said further panels extending the same distance between adjacent hinge lines respectively as said first and third panels and an interconnecting bar pivotally connected to corresponding locations on the panels of the pair of interconnecting mechanisms to maintain corresponding ones of said panels parallel.

13. A platform support system according to claim 12 wherein said interconnecting bar extends from said fourth hinge line to the hinge line between the panels of said further pair.

14. An interconnecting mechanism for rigidly supporting platforms for movement along a given path, said mechanism comprising first, second, third and fourth outer support panels each being rigidly resistant to bending and twisting and hingedly connected together at their edges at displaced locations along each of first, second, third and fourth mutually parallel hinge lines to form a generally box-like construction, said panels being of a length to maintain said third and fourth hinge lines at a first distance from said second hinge lines, a pair of control braces pivotally connected to each other along a fifth hinge line and pivotally connected to said outer support panels along said third and fourth hinge lines, respectively, said control braces being of a length to maintain said fifth hinge line at the same distance from said third and fourth hinge lines as said first hinge line, a control link pivotally connected to said control braces along said fifth hinge line and connected to a pivot fixed with respect to said second hinge line, said control link being of a length such that the distance between said fifth hinge line and said pivot is the same as the distance between said pivot and said second hinge line.

15. An interconnecting mechanism according to claim 14 wherein said control link and fixed pivot are positioned approximately midway across the width of the panels and wherein said third and fourth panels have openings extending from their base connected edges for allowing said panels to swing over said control link and fixed pivot.

16. An interconnecting mechanism according to claim 15 wherein each of said control braces extends diagonally from said control link out to the side edges of said panels at said third and fourth hinge lines.

17. An interconnecting mechanism according to claim 14 wherein said outer support panels is of open framework construction comprising side elements and diagonal struts which cooperate to form an octahedron.

18. An interconnecting mechanism according to claim 17 wherein each of said outer support panels is

provided with fittings at the ends of said side elements, said fittings being pinned to corresponding fittings in an adjacent panel.

19. An interconnecting mechanism according to claim 18 wherein said control braces each comprise a pair of branches extending diagonally from said control link to collars adjacent the fittings on said outer support panels.

20. An interconnecting mechanism according to claim 14 wherein said outer support panels are of flat sheet material segments arranged to form polyhedrons wherein said outer support panels are in the shape of octahedrons.

21. An interconnecting mechanism according to claim 14 wherein said control braces are panels of sheet material segments arranged to form polyhedrons.

22. An interconnecting mechanism according to claim 14 wherein said outer support panels and control braces are hinged together with strap type hinges.

23. A platform support system comprising a platform member, a base member, a pair of interconnecting mechanisms each interconnecting said platform and base members, at least one of said interconnecting mechanisms comprising four outer support panels hingedly connected together at displaced locations along each of four parallel hinge lines at their edges to form a box-like construction, means for hingedly connecting said panels to said platform and base members along first diagonally opposed ones of said hinge lines respectively, each of said outer support panels being of rigid construction, thicker at the center than at the edges and resistant to compressive forces between hinge lines along opposite edges, and being further resistant to tensile forces, bending and twisting forces, linkage means for varying the mutual displacement of the other diagonally opposed hinge lines in accordance with pivotal movement of said panels about one of said first diagonally opposed hinge lines.

24. A platform support system according to claim 23 wherein the remaining one of said interconnecting mechanisms is of the same construction as said one interconnecting mechanism.

25. A platform support system comprising a platform member, a base member, a pair of interconnecting mechanisms each interconnecting said platform and base members, one of said interconnecting mechanisms comprising first, second, third and fourth outer support elements hingedly connected together along four parallel hinge lines to form a four sided construction, means for hingedly connecting said elements to said base and platform members at first diagonally opposed ones of said four parallel hinge lines, linkage means for varying the mutual displacement of the other diagonally opposed hinge lines in accordance with pivotal movement of said elements about one of said first diagonally opposed hinge lines, the other interconnecting mechanism comprising fifth and sixth outer support elements hingedly connected to each other and to said platform and base members respectively, said fifth and sixth elements extending parallel to two mutually adjacent ones of the first four elements when said platform member is parallel to said base member and a connector bar extending between and pivotally connected to corresponding locations on said interconnecting mechanisms.

26. A platform support system according to claim 25 wherein said connector bar extends between one of the first diagonally opposed hinge lines of the first interconnecting mechanism and the hinge line between said fifth and sixth outer support elements.
